(57) **CLAIM**

The ornamental design for a sterilizing cleaner, as shown and described.

DESCRIPTION

FIG. 1 is a front perspective view of the sterilizing cleaner showing our new design;
FIG. 2 is a front view thereof;
FIG. 3 is a rear view thereof;
FIG. 4 is a left side view thereof where the right side view is a mirror image;
FIG. 5 is a top plan view thereof;
FIG. 6 is a bottom plan view thereof;
FIG. 7 is a back perspective view thereof;
FIG. 8 is an exploded view showing a state in which the sterilizing and cleaning part is separated from the main body;
FIG. 9 is a reference view showing the use state in which the claimed design has been installed on the bed; and,
FIG. 10 is a reference view showing the use state in which the claimed design has been installed and operated on the bed.
The broken lines depict portions of the sterilizing cleaner that form no part of the claimed design.

1 Claim, 10 Drawing Sheets
